UNITED STATES PATENT OFFICE.

PAUL ARMAND DROUARD AND LEON DESIRÉ DROUARD, OF ROUEN, FRANCE.

BALLAST-MACHINE.

1,181,951.

Specification of Letters Patent.

Patented May 2, 1916.

Application filed August 24, 1911. Serial No. 645,732.

To all whom it may concern:

Be it known that we, PAUL ARMAND DROUARD and LEON DESIRÉ DROUARD, both residing at 2bis Boulevard Jeanne d'Arc, 5 Rouen, France, have invented certain new and useful Improvements in Ballast-Machines, of which the following is a specification.

Railway companies in order to assure the setting and draining of their lines employ 10 screened gravel as ballast. This gravel is passed through a screen of a definite mesh and the large pieces are broken to such a dimension that they can pass through a ring 15 the diameter of which varies from 7 to 10 cm. This ballast is obtained from alluvial soils and is generally submerged beneath the level of the water. Hitherto, the most improved means employed permitted of extracting and 20 washing the gravel by means of machines called excavators, screening machines and washing machines. This apparatus permitted of loading the washed ballast on to the car, but let the sand and the water fall 25 back between the track of the excavator and that of the car being loaded. There thus resulted a blocking-up and a rapid deterioration of the tracks. Moreover, the working 30 of and access to the machines was very difficult, because the works were continuously covered with water. The sand, which amounted sometimes to 40% of the gravel 35 extracted was subsequently loaded on to cars with shovels. The ballast obtained by means of the excavators, screening and washing machines contained large pieces which had to be removed and broken by hand when placing the ballast on the tracks. This process was accomplished by serious disadvantages. 40 Besides the accidents, to which the stone-breaker was liable, the operation of breaking was always long, of but slight interest to the worker, very costly and very irregular. However great was the care employed some large pieces were always overlooked. 45 The irregularity of the work prevented its being performed as piece-work, supervision was very difficult, the output of each worker very low and consequently very costly. For a long time efforts had been 50 made to do it mechanically, and mechanical screening was proposed for separating out the large pieces. These latter were then

taken and transported to a crushing mill at a fixed spot in the quarry. The broken 55 pieces were then again taken, loaded on to the car and sent off. By working thus, however, and notwithstanding the repeated handling of the gravel, which is very costly, the quality of the ballast was very seriously 60 affected by the removal of the large pieces, because it was materially impossible to 65 remix them properly in the mass again. The large broken pieces form angular pieces which grip the sleepers and prevent displacement or spreading of the lines. It is therefore of great importance to mix these angular pieces proportionately throughout the 70 whole mass, so as to obtain a homogeneous ballast of first quality, but this result was 75 not obtained with the process above described. Furthermore, the mills hitherto employed for crushing the ballast delivered stones which were very irregular in size and frequently but imperfectly complying with 80 requirements. The machine worked by pressure and consequently produced a much greater proportion of fine material than results when breaking by hand with a hammer. The apparatus forming the subject matter 85 of the present invention comprises a machine for crushing large rocks, thereby producing a gravel used as ballast.

We will now describe our invention with reference to the accompanying drawings, in 85 which:—

Figure 1 is a front view of the plant. Fig. 2 is a plan view of the plant. Fig. 3 is a detail of the decanting basin situated at the lower part of the sand elevator. Fig. 4 is a 90 section along the line B—B of Fig. 3.

The ballast machine forming the subject matter of this invention is characterized by the combination of an excavator, two screening machines, a stone-breaking machine, a 95 pump, and two conveyors, all of which permit of mechanically and simultaneously effecting the following operations:—extracting the rough gravel from the quarry, cleaning the pebbly mass, separating out and 100 breaking the large pieces and returning them to the cleaned mass, and automatically loading the sand on the one hand and the gravel on the other hand on to two parallel cars. In its rotary movement the screen carries 105 along with it the stones and sand and allows

those elements that can be used without being broken to pass through, while the large pieces continue their passage to the end of the screen 3 from where they fall into the 5 stone-breaking machine 4. During this screening of the gravel a perforated tube located in the center of the screen is supplied with water under pressure by means of a powerful pump and continuously sprinkles 10 the rotating material, and thus effecting a thorough washing of the large pieces.

The stone-breaking apparatus 4 consists of two sets of superimposed cylinders rotating at a very high speed and each provided 15 on its periphery with special teeth or recesses offering angles for engaging with the stones. The very high speed at which the cylinders rotate is for the purpose of effecting a violent blow at the moment when the 20 stone passes between the cylinders so as to produce the minimum quantity of fine material and thus avoid the very great disadvantage referred to above with stone-breaking mills as ordinarily employed. The stones so 25 broken now fall into a suitable conveyer 5 which conveys them directly to a car 6. The material that can be employed without being broken and which has passed through the screen 3 falls into an inclined chute 7 30 and is carried along by the washing water into a rotary screen 8 which is of the same type as the screen 3, but of much smaller mesh so that only the sand, which is considered as a by-product, passes through. During 35 its rotary movement the screen 8 carries along with it the stones, the sand and the clayey materials, while a powerful sprinkling with water, obtained as previously by means of a central perforated tube, completely 40 cleans the gravelly mass and carries along with it the sand and the dissolved clayey materials through the perforations of the screen-cylinder. Only the stones 45 continue their passage, and at the end of the screen fall into a car 6, which they reach entirely cleaned. The arrangement of the 50 parts is such that the broken pieces fall into the car at about the same spot as the screened material, with which they are again automatically 55 mixed. The angular pieces of the ballast will thus be distributed uniformly and not superficially throughout the entire mass, which considerably improves its quality. In brief, the cleaned ballast contains as 60 broken pieces the whole of the large stones which it previously contained. The sand and the water used for washing pass through the perforations of the screen 8 and fall into a chute 9 which conducts them into a decanting basin 10 through which rotates a 65 chain and bucket conveyer 11, the buckets of which are perforated. The sand is deposited at the bottom of the basin whereas the washing water and the dissolved clayey materials 70 pass through a perforated wall surrounding

the bucket-chain. This water is returned far back to the cutting through a suspended pipe 14, and the sand which has become deposited at the bottom of the basin is taken up and after being drained from water by the 75 bucket-chain 11 is discharged on to a suspended conveyer which discharges it mechanically on to a car 13 situated on a track parallel to that of the ballast. All the useful products and by-products taken from 80 the ground are thus loaded mechanically on to cars ready to be employed, while the clayey, argillaceous materials are carried away with the washing water and returned to the cutting sufficiently far away so as 85 not to be taken up again by the excavator.

The plant is completed of course by the machines and accessories for driving the various apparatus, and it will only be necessary to enumerate the same.

85

15 is a pump with a rose for drawing the water from the cutting to be used for washing; 16 are the pipes for conducting the washing water to the screen; 17 is the engine used for moving the whole plant from 90 place to place; 18 is the engine for driving the screen 8; 19 is the engine for driving the excavator 1; 20 is the boiler for supplying steam to the engine of the pump 15 and to the engines 17, 18 and 19; 21 is the engine 95 for driving the screen 3; 22 is the engine driving the stone-breaking machine 4; 23 is the machine for driving the sand conveyer; 24 and 25 are the boilers for supplying steam to the engines 21, 22 and 100 23; and 26 is the hoisting winch of the excavator.

Besides its character as a whole, which consists in a grouping of various mechanical parts permitting of obtaining a definite work, the invention comprises improvements in detail in the cleaning of the stones and sand, and in the stone-breaking cylinders. The former of these improvements consists in the use of the decanting basin 105 10 (Figs. 3 and 4) in which works the chain provided with perforated buckets 11 for taking up the sand again and draining it. This basin comprises an inner chamber 10^a and an outer chamber 10^b separated by a 110 perforated partition 27. The sand is deposited in the inner chamber 10^a from where it is removed by the buckets 11, and the washing water with the dissolved argillaceous materials passes through the perforated 115 wall 27 which completely surrounds the inner chamber 10^a and falls into the outer chamber 10^b from where it is conveyed by the pipe 14 back to the cutting.

120 What we claim as our invention and desire to secure by Letters Patent is:—

In an apparatus for producing ballast, the combination of a screening and washing device, a crushing device, means for delivering the oversize from the screening and 130

washing device to the crushing device, a second screening and washing device adapted to receive the undersize from the first screening and washing device, and means
5 for remingling the material from the crushing means and the oversize from the second screening and washing device.

In testimony whereof we have affixed our signatures in presence of two witnesses.
